Primary Examiner — Sandra Snapp(74) *Attorney, Agent, or Firm* — Sutherland Asbill & Brennan LLP**CLAIM**

The ornamental design for an odor control cartridge, as shown and described.

DESCRIPTION

FIG. 1 is an isometric view showing a first embodiment of an odor control cartridge design;

FIG. 2 is a top plan view of the odor control cartridge of FIG. 1;

FIG. 3 is a front elevation view of the odor control cartridge of FIG. 1;

FIG. 4 is a right side elevation view of the odor control cartridge of FIG. 1; and,

FIG. 5 is a top plan view of a second embodiment of an odor control cartridge design, wherein an isometric view, an elevated front view, and an elevated right side view are represented in FIGS. 1, 3, and 4, respectively.

The broken lines are for illustrative purposes only and form no part of the claimed design.
